UNITED STATES PATENT OFFICE.

ARTHUR MORTON, OF SEATTLE, WASHINGTON.

WIRE CABLE.

Application filed January 27, 1927. Serial No. 164,037.

This invention relates to an improvement in wire cables designed more particularly for use in connection with logging operations wherein the cable travels over a grooved pulley.

The main object of the invention is the provision of a cable in which the outer strands conform in curvature to the curvature of the grooved pulley, whereby the wear incident to the normally circular strand is avoided and the breaking up of said strands into slivers and threads, so common in cables of this type, is entirely dispensed with.

The invention is illustrated in the accompanying drawings in which:

Figure 1 is an enlarged sectional view showing a multi-strand cable constructed in accordance with the present invention.

Figure 2 is a sectional view on an enlarged scale of one of the outer strands, showing the curvature of the pulley engaging surface.

The improved cable is shown as a multi-section cable made up of a center of hemp or the like, as at 1, and a series of independent sections 2 each made up of an inner wire 3 surrounded by circular wires of small diameter 4 and an outer section layer of wire strands 5.

Ordinarily, these outer strands, are circular so that in cooperation with the curvature of the pulley, they are gradually worn away. That is to say, in the use of the cable, the outer circular strands are worn away until they present a surface which is concentric with the surface of the pulley. This wearing away of the strands breaks up the same into slivers and thread-like projections which are, of course, objectionable.

In the present invention, these outer strands 5 are formed on their outer surfaces at 6 on a plane which coincides with the curvature 7 of the pulley. Therefore, there is no wearing down of the cable incident to the non-conforming surfaces between the cable strands and pulley and consequently the cable wears smooth and even and without slivers.

Therefore, the cable originally constructed of a certain diameter with a certain strength, does not reduce its diameter as rapidly and therefore reduce its strength when the outer strands are constructed as outlined in the present invention as when said strands are constructed in the usual manner.

What I claim to be new is:

A cable composed of a central core of hemp strands and a plurality of adjacent subcables arranged around the hemp core, all in contact with each other and with the hemp core, each subcable comprising a central round core and intermediate round strands smaller in diameter than the diameter of the central round core and surrounding the central round core and outer strands greater in diameter than the diameter of the intermediate strands and surrounding the intermediate round strands, each of the outer strands being semi-circular in cross section upon their nether surfaces and the outer surface of each said outer strand being formed to represent an arc of a complete circle surrounding the central hemp core.

In testimony whereof I affix my signature.

ARTHUR MORTON.
